UNITED STATES PATENT OFFICE.

EILEF KAAKS, OF KONGSBERG, NORWAY.

COMBINATION-TOOL.

1,187,842.

Specification of Letters Patent. Patented June 20, 1916.

Application filed May 26, 1915. Serial No. 30,574.

To all whom it may concern:

Be it known that I, EILEF KAAKS, a subject of the King of Norway, residing at Kongsgberg, Norway, have invented certain new and useful Improvements in Combination-Tools; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

My invention relates to improvements in combination tools of the class which comprises a number of tools or instruments contained in a single handle or carrier.

The object of my invention is to provide a tool body or holder which will permit of a plurality of tools or implements differing in character to be contained and conveniently arranged within the body or holder and be easily brought into and out of working position when required.

The invention consists in providing a main body for tools or implements of one character, and a detachable side portion for tools or implements of a different character, whereby the body may be divided for the purpose of reducing the size thereof and to permit the independent use of certain implements.

In the accompanying drawings—Figure 1 is a side view of the main body portion of my improved tool, with the implements opened out. Fig. 2 is a top view of Fig. 1, with only one implement partly extended. Fig. 3 is an end view of Fig. 2, seen from the right. Fig. 4 is a bottom view of the body portion shown in Fig. 1. Fig. 5 is a plan view of the outside of the detachable side portion. Fig. 6 is an end view of Fig. 5, and Fig. 7 is an inside view of the detachable portion having an extra implement attached thereto.

The main part B of the body or handle, shown in Figs. 1 to 4, comprises two cheeks or sides, b, b', which are spaced apart by connecting pins or rivets c at the four corners and edges. On the pins c between the cheeks are pivoted, in the usual manner, a plurality of elements adapted to lie between or be extended beyond the ends or edges of the cheeks. The pin in the upper left hand corner of the handle carries a gimlet, 1, file

2, button hook 3 and an arm 4, all being arranged to swing in the same direction to bring them to lie within the body. In the free end of the arm 4 is centrally pivoted a combination implement consisting of a nail file and brush 5, on one side of the pivot and an ear spoon 6 on the other side of the pivot, so that the file or spoon may be alternately projected beyond the end of the arm 4. A long coarse saw 7 is pivoted on the pin c at the upper right hand corner of the body and lies when within the latter between the file 2 and hook 3, as shown in Fig. 2. On the pin c at the left hand corner of the body is pivoted a can opener 8, punch 9, screw-driver 10 and a fine saw 11; and on a rivet or pin c between the ends of the handle is pivoted a cork-screw 12 and a bodkin 13, all being arranged to swing in the same direction and lie within the body, as shown in Fig. 4. Below the gimlet 1, and between it and the can opener 8 is slidably mounted a knife 14. This knife carries a laterally projecting threaded bolt 14' which extends through a longitudinal slot b² formed in the side b' of the body and is clamped to the latter, so as to hold the knife in position, by a nut 15. Clamped on the bolt 14, by means of the nut 15 is a bracket formed with two bearing arms 16 which project beyond the edges of the sides of the body, and journaled in the arms 16 are two disks 17 which operate as means for sharpening knives. A key, 18, may also be clamped to one side of the body by the bolt and nut. Between the sides b, b', in a space left between the free end of the hook 3 and the right hand end of the body, is mounted a tape measure. Above the bottom row of implements, between the sides b, b' is located a weighing scale, consisting of a spring 20, one end of which is connected to the side b while the other end is connected to a pointer 21 projecting through and slidably in slot 22 in the side b, a scale 23 being marked on the edge along one edge of the slot. Articles, such as letters and the like, to be weighed are connected to the pointer by any suitable means (not shown) commonly used for such purpose, as for instance, a pair of spring arms adapted to be hung on the pointer.

The detachable side A, shown in Figs. 5 to 7, is formed with a longitudinal channel a open at both ends and provided with a laterally extending flange a' on each side of the channel. This side A is detachably con-

nected to the main part or body B by means of press buttons C provided on the flanges a' and adapted to take into sockets D formed in the side piece b, of said body. A table 5 knife E and a table fork F of substantially the same width as the channel a are slidably mounted in the channel a of the side. They are secured to said side in their retracted and extended positions by means of threaded 10 bolts G projecting laterally from the shanks of the knife and fork and extending through a longitudinal slot a^2 in the bottom of the channel a . Nuts H on the bolts G operate to clamp the parts to the side. If 15 desired, a spoon I may be pivoted on the bolt of the fork and clamped to the back of the detachable side A, as shown in Fig. 7. In order to extend the spoon beyond the end 20 of the side without extending the fork F, the latter is turned on its bolt so as to lie within the channel.

Claims:

1. A combination tool having a detachable side formed with an open ended longitudinal channel and lateral flanges, implements slidably mounted in said channel, and means on the tool and flanges for detachably connecting the side to the body of the tool. 25

2. A combination tool having a detachable side formed with a longitudinal implement 30 containing channel and lateral flanges formed on the edges of said channel, and press-buttons on the flanges arranged to engage sockets in the body of the tool for detachably connecting said side to the latter. 35

In testimony that I claim the foregoing as my invention, I have signed my name in presence of two subscribing witnesses.

EILEF KAAS.
